UNITED STATES PATENT OFFICE.

PAUL SHVING, OF BERKELEY, CALIFORNIA.

FIRE-FLAIL.

1,238,583.

Specification of Letters Patent. Patented Aug. 28, 1917.

Application filed April 10, 1917. Serial No. 161,069.

To all whom it may concern:

Be it known that I, PAUL SHVING, a citizen of the United States, residing at Berkeley, in the county of Alameda and State of California, have invented new and useful Improvements in Fire-Flails, of which the following is a specification.

This invention relates to flails especially adapted to be used for fighting fire and it 10 consists in the novel features hereinafter described and claimed.

An object of the invention is to provide a flail of the character stated which is of simple and durable structure and which is 15 cheap to manufacture, and which may be used to advantage for beating out fire which may be burning in grass, brush or the like.

With this object in view the flail comprises a panel of asbestos which is stiffened 20 and braced by sheet metal on both sides. A bail is pivotally connected with the said sheet of metal and a handle staff is swiveled to the intermediate portion of the bail. In operation, the device is used by swinging 25 the same over the head of the operator and by bringing it down upon the fire which is burning at the ground in grass or brush thus beating out the flames and extinguishing the coals and sparks.

30 In the accompanying drawings:—

Figure 1 is a perspective view of the flail; Fig. 2 is an edge view of the same.

Fig. 3 is a transverse sectional view through the panel of the flail.

35 The flail comprises a panel which consists of a sheet of asbestos 1 having sheets of tin plate 2 or other suitable metal applied to both sides thereof. The sheets 2 add rigidity to the sheet 1 and brace the 40 same and hold the said sheet of asbestos in proper shape. The sheet 2 at one side of the sheet 1 is bounded upon its edges by strips 3 which serve to strengthen the general structure of the panel and prevents the 45 said sheet 2 from being bent or twisted out of shape. A bar 4 is applied to one end portion of the sheet 2 which carries the strips 3 and is provided with ends which extend beyond the side edges of the said sheet 50 2. A bail 5 is pivotally connected at its ends with the projecting end portions of the bar

4, and a handle staff 6 is swiveled to the intermediate portion of the said bail 5. The swivel connection between the handle staff 6 and the bail 5 is such that the said staff 55 may substantially have universal swinging or turning movement with relation to the said bail. The connection between the bail 5 and the bar 4 is such that the said bail may have swinging movement with relation 60 to the bar and the panel of which it is a part.

In operation the device is used similar to that of a flail which is employed for threshing grain and the operator grasps the staff 65 6 in his hand and swings the panel over his head and brings the same down upon the fire which is at the surface of the ground in grass or brush with sufficient force to put the fire out and extinguish the sparks. In 70 view of the fact that the asbestos is a non-conductor of heat the metallic sheet 2 which is located at the upper or top side of the panel, is prevented from becoming heated and hence it is not warped or readily bent 75 or twisted out of shape.

From the foregoing description taken in conjunction with the accompanying drawing, it will be seen that a fire fighting flail of simple and durable structure is provided 80 and that the same may be efficiently used for extinguishing fire in grass or low brush.

Having described the invention what is claimed is:—

1. A flail comprising a panel including 85 a sheet of non-heat conducting material, a bail pivoted to the panel and a handle staff swiveled to the bail.

2. A flail comprising a panel including a sheet of heat non-conducting material, a 90 metallic sheet applied to the first mentioned sheet, a bail pivoted to the panel and a handle staff swiveled to the bail.

3. A flail comprising a panel including a sheet of heat non-conducting material, a 95 metallic sheet applied to the first mentioned sheet, bracing strips applied to the edge portions of the second mentioned sheet, a bail pivotally connected with the panel and a handle staff swiveled to the bail.

In testimony whereof I affix my signature. 100
PAUL SHVING.
